UNITED STATES PATENT OFFICE.

JOSEPH E. CAPLINGER, OF SMITHFIELD, KENTUCKY.

WATER-GATE.

SPECIFICATION forming part of Letters Patent No. 402,139, dated April 30, 1889.

Application filed December 10, 1888. Serial No. 293,207. (No model.)

To all whom it may concern:

Be it known that I, JOSEPH E. CAPLINGER, a citizen of the United States, residing at Smithfield, in the county of Henry and State of Kentucky, have invented certain new and useful Improvements in Water-Gates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to flood-gates; and it has for its object to provide a gate of this character which will automatically open or close as the condition of the stream may require; and it consists in certain novel features 20 of construction and peculiar combinations of parts, as will be hereinafter fully explained in the annexed specification, and particularly pointed out in the claims, reference being had to the accompanying drawings, in which—

25 Figure 1 is a perspective view of my improved flood-gate. Fig. 2 is a detail view of one of the hinge-posts. Fig. 3 is a detail cross-section on the line 3 3, Fig. 2; and Figs. 4 and 5 are detail views illustrating the latch mechanism.

30 In the practical construction of my gate I embed in the bottom of the creek a horizontal sill, A, to which (one at each end thereof) are secured the posts B B, which may have their lower ends extended about three (3) feet 35 and passed through the sill into the ground, and thereby assist in keeping the sill securely in place.

C denotes the gate, consisting of the two 40 sections C' C', which are hinged to the posts B B, as shown in Fig. 2. By reference to said figure it will be seen that I form one corner of the posts B with cutaway portions B', forming recesses in which are fitted the hinge-bars C² of the gate-sections C' C'. These sections are connected to the posts B B by means 45 of spring-hinges D D, which normally tend to close the said sections C' C' against a central stop or latch, E.

50 The advantages of hinging the gate-sections in the manner described will presently be explained.

The gate-sections C' C' each consist of the hinge-bar C², the end bars, C³, and the horizontal boards C⁴ C⁵, the lower one of which is preferably about two feet wide, to keep trash from accumulating. The lower ends of the bars C³ are cut away, as at c c, and are provided near the lower edges of such ends with inwardly-projecting studs c' c', which engage with the end e of the latch E, as shown.

In Figs. 4 and 5 the construction of the latch E is clearly illustrated. Projecting upward from the sill A, inside of the gate, is a short post, G, the upper end of which is bifurcated, 65 as at g, in which the rear arm, e², of the latch E is pivoted upon a cross-pin, g'.

The latch E consists of the enlarged head e, having an inclined face, e', a notch, e³, which engages the studs c' c' when the gate is closed, 70 and thereby locks the same, a downwardly-extending weighted portion, E⁸, the pivotal arm e², and the lateral wings or extensions E⁴.

The operation of my improved gate is as follows: The same being in position, as shown 75 in Fig. 1, the notch in the gravity-latch E engaging the studs c' c' will hold the gate locked. Now, when a sudden rise of the water (which flows in the direction shown by the arrow) occurs, the increased pressure of the same 80 against the lateral wings E⁴ raises the gravity-latch and releases the notched end e (which passes through the opening c) from the studs c'. The water pressing against the gate then swings the sections outward in the direction of the arrows against the tension of the spring-hinges D D, and thereby permits 85 an uninterrupted flow of the water and débris. As the tide recedes and the pressure of the water is gradually decreased, the spring-hinges 90 will gradually close the gate-sections. During this movement the studs c' will strike against the inclined end of the latch and raise it until the studs register with the notch e³, which allows the latch to fall by gravity 95 and hold the gate locked until a sufficient pressure is again exerted against the wings E⁴.

By hinging the gate-sections in the manner described the spring-hinges are more effectively protected from the débris and swiftly-flowing tide, as the forward portion of the posts will deflect the same and prevent any unnecessary accumulation of dirt, &c., about the hinges. It will be seen that by construct-

ing the gate as set forth it always accommodates itself to the existing conditions of the stream. Its operation is exceedingly simple, and its cost of construction is very small in comparison with similar devices now in use.

Having thus described my invention, what I claim, and desire to secure by Letters Patent, is—

1. The combination, with the posts B, the gate-sections C' C', hinged thereto, and springs for normally throwing said sections to a closed position, (the lower inner ends of the sections being provided with projecting studs c' c'), of the gravity-latch E, said latch hinged at its rear end forward of the gate, provided with a water-resistance surface at its rear end, its forward end inclined and provided with a notch adapted to engage the studs c' c' when the latch is dropped, the forward end of said latch adapted to rise from engagement with the studs when increased pressure is applied against the rear end of the latch, substantially as and for the purpose specified.

2. The combination, with the posts B B, the gate-sections C' C', hinged to said posts, and springs for forcing said sections normally into a closed position, said sections provided with inwardly-projecting studs c' c', of the gravity-latch pivoted forward of the gate and projecting to the rearward thereof, said latch consisting of the body portion e', having an inclined end, e², a notch, e³, adapted to engage the studs c' c', a rearwardly-extending arm, e, pivoted, as shown, and lateral wings or extensions E⁴, extending transversely across the rear face of the latch below its pivotal point, said arms forming a resistance-surface for the water-pressure, substantially as and for the purpose set forth.

In testimony whereof I affix my signature in presence of two witnesses.

JOSEPH E. CAPLINGER.
